UNITED STATES PATENT OFFICE.

RICHARD MERCER, OF HARROW, AND FRANK TENCH, OF WEST NORWOOD, LONDON, ENGLAND, ASSIGNEES, BY MESNE ASSIGNMENTS, TO AUTOMATIC ELECTRIC INC., OF CHICAGO, ILLINOIS, A CORPORATION OF DELAWARE.

MANUAL TO AUTOMATIC SYSTEM.

Application filed May 9, 1924, Serial No. 711,998, and in Great Britain May 31, 1923.

The present invention concerns improvements in or relating to telephone systems and more particularly to those systems in which calls are set up from a manual subscriber over numerical switches controlled by an operator. In systems of this kind it is desirable in order that each operator may be able to work at full speed that she shall be able to make use of a plurality of impulse senders at a time, say three or four. If this is done it becomes very uneconomical to provide the required number of impulse senders individual to each operator and accordingly they are arranged in large groups accessible in common to a number of operators. The main object of the invention is to provide improved circuit arrangements for associating an idle impulse sender with a trunk line and for controlling it so as

20 to set up the desired connection.

According to one feature of the invention, on an operator performing an operation in connection with the selection of an idle line, an idle link circuit becomes associated 25 with the operator's key set, the line selected and an idle impulse sender.

Another feature of the invention is that an operator's key set is associated with an idle link circuit over a forwardly hunting 30 switch, the said link circuit being associated with a trunk line by an operation on the part of the operator and with an idle impulse sender by the operation of a hunting switch.

A further feature is that an operator's 35 key set is associated with an idle link circuit over a forwardly hunting switch, said link circuit being associated by an operation on the part of the operator with both the selected trunk line and an idle impulse sender.

40 Other features relate to an improved circuit arrangement for automatically initiating the generation of impulses after all the digits have been stored and to an improved holding circuit whereby an impulse sender 45 may be controlled from the selected line over the link circuit switches.

These features and others not specifically mentioned at this point will be more fully appreciated from the following description 50 taken in conjunction with the accompanying drawings. It should be understood that the embodiment described is by way of example only and that various modifications may be

made in the individual circuits without exceeding the scope of the invention.

55 Referring now to the drawings, Fig. 1 is a general layout or trunking diagram; Figs. 2, 3, and 4 show by means of the usual circuit diagrams one embodiment of the circuit arrangement employed in connection with the layout shown in Fig. 1; and Figs. 5, 6, and 7 show a desirable modification of the arrangement shown in Figs. 2, 3, and 4.

Figure 2 shows one of the trunk lines extending through a "B" operator's position; 60 Fig. 3 shows the operator's key set together with the switch for associating it with the operator's link circuits, and also one of the link circuits, together with the switch for connecting the link circuit with an idle register sender; and Fig. 4 shows one of the register senders.

70 In the modification shown in Figs. 5-7, Fig. 5 corresponds to Fig. 2; Fig. 6 corresponds to Fig. 3; and Fig. 7 corresponds to Fig. 4.

In Figure 1 is shown, as above stated, the general layout of the apparatus used in extending a connection from a manual subscriber to an automatic subscriber by way of the mechanical tandem operator's position and this operation will be briefly described. 80

When the subscriber initiates a call, the A operator at the manual exchange is signalled in the usual manner and she thereupon inserts the answering plug P_1 of the cord circuit O , for instance, in the jack J_1 . Upon 85

learning the subscriber's requirements, she will give the required number to the B operator over an order wire which is not shown. She will then be assigned a junction line, for instance, the junction line L_2 , and will thereupon insert the plug P_2 into the jack J_2 . When the B operator presses the assignment key corresponding to the line L_2 , which she has assigned, the sender selector SS_1 corresponding to the outlet with which the wipers of the outlet finder OF are in engagement will hunt to find an 90

idle set of impulse sending equipment which thereupon becomes associated with the key set K . The B operator will then set up the number on the key set and in accordance with the first digit, the first storage relay group SR_1 will be influenced over the outlet finder in the position shown, back con- 100

tact and armature T_1 , sender selector SS_1 , armature W_1 and its back contact, back contact and armature Z_1 and transfer switch TS in first position. The transfer switch TS is moved one step as each key is released so that the various digits are recorded on the appropriate sets of storage relays $SR_1, SR_2, SR_3 \dots SR_7$.

When the B operator presses her start key 10 (assuming that the plug P_2 has already been inserted in the jack J_2), the armature T_1 , W_1 and Z_1 will be operated so that the storage relay sets are connected by way of converting relays CR to the impulse sender IS and this latter is connected to the corresponding junction line by way of the connecting point C_1 . The required impulses are then sent out by the impulse sender as controlled by the storage relays and these impulses will operate the selector E and succeeding selectors and a connector (not shown). The transfer switch is moved on one step at the end of each train of impulses and thus the appropriate storage relay set 20 is brought into operation to control the generation of each successive digit.

The outlet finder OF is moved on one step when the start key is pressed; consequently the key set K is then associated with another outlet and the operator may commence setting up another connection, as soon as she has finished with the previous one.

Since in the arrangement shown four outlets are provided, the sending of impulses may take three times as long as the actual setting up of the number without the operator being held up owing to lack of outlets.

Referring now more specifically to Figs. 2, 3 and 4, the operation involved in the sending of a call will be traced through in detail. The A operator in the manual exchange after ascertaining the calling subscriber's wishes will communicate with the B operator at the mechanical tandem exchange over an order wire which is not shown. The B operator will thereupon assign to the A operator an idle inter-exchange trunk, for instance, that comprising conductors 1 and 2, at the same time pressing the corresponding assignment key 3. The effect of this is to energize the assignment relay 4 which thereupon closes its contacts 5, 6, 7, 8 and 9. The closing of the contacts 5, 6, 7 and 8 prepares circuits for the relays 10, 11, 12 and 13, respectively, while at contact 9 earth is connected to lead 100 over back contacts and armatures such as 9 and 19 on all the other assignment relays in the position.

A circuit is thereupon completed from this earth over lead 100, through relay 109, wiper 113 and the contact on which it is standing, normally closed spring 114 of the sender disconnect key, armature 121 and its back contact and through relay 120 to bat-

tery. Relays 120 and 109 energize in series in this circuit and the latter at contact 126 opens a point in the circuit of the driving magnet 123, another point in which circuit is closed at armature 125 by relay 108 which is also energized by earth on lead 100. As, however, relay 108 is slightly slow to pull up, this circuit for driving magnet 123 is never completed in the normal working of the apparatus even should earth be connected to lead 170', which will not always be the case. Relay 120, upon energizing, at armature 134 completes a circuit from earth at armature 140 for driving magnet 162 and cut off relay 119 in series and at armature 135 connects test wiper 146 to the junction of relay 119 and magnet 162 by way of armatures 132 and 161 and their resting contacts. In case the wiper 146 is resting on a contact associated with an idle sender, there will be no earth present on this contact and relay 119 will at once energize. If, however, the wiper 146 finds earth on the contact with which it is in engagement relay 119 will be short circuited and the driving magnet 162 will be energized and will operate intermittently under the control of its interrupter contact 163 to step the wipers 143-146 inclusive, around until wiper 146 encounters a contact which is not earthed. When this occurs, relay 119 is no longer short circuited and energizes in the following circuit: battery, stepping magnet 162, interrupter contact 163, winding of relay 119, front contact and armature 134, back contact and armature 140, earth. Relay 119, upon operating, at armatures 127, 128 and 130 connects the wipers 110, 111 and 112 through to the wipers 143, 144 and 145, respectively, by way of back contacts and armatures 136, 137 and 138. At armature 133, relay 119 shunts contact 134 so as to complete a locking circuit for itself, at armature 132 opens the circuit of the driving magnet 162 and places earth on the test wiper 146, and at armatures 129 and 131 connects battery and earth respectively to leads 102 and 103 extending to the trunk circuit.

The earth connection to lead 103 is by way of the normally closed spring 117 of the sender disconnect key and a connection from this also extends to the sender guard lamp 164 which thereupon lights to show that the outlet is in use. The effect of connecting battery and earth to leads 102 and 103 is to complete an energizing circuit for relay 10, which circuit may be traced from battery on lead 102, normally closed springs controlled by armature 16, winding of relay 10, armature 5 and its working contact to earth on lead 103. Relay 10 upon operating, at armatures 14 and 18 connects the outgoing trunk line to the impulsive leads 105 and 107, at armature 15 closes a circuit from the normal earth on lead 106 for the assign-

ment lamp 27, at armature 16 opens its initial energizing circuit and completes a locking circuit for itself by way of normally closed contact 26 controlled by the busy or cancel key, and at armature 17 shunts armature 5 so that its circuit may not be opened when the assignment relay falls back as it does when the assignment key is released. The operator keeps the assignment key 10 pressed until the assignment lamp 27 lights whereupon she knows that the outlet finder and sender selector switches have functioned correctly and that her key set is now connected through to an idle set of impulse sending equipment. The time required for this operation to take place will in general be very small; probably in most cases the operator would naturally press the key sufficiently long.

20 The operations which have so far taken place are, therefore, the association of the single set of digit keys with an idle impulse sender by way of an idle outlet and the preparation of the association of this impulse sender with the trunk line assigned. The operator may now therefore proceed to set up the wanted number on the digit keys, which number we will suppose for the sake of example is 8645321.

30 When she presses the key 8 a circuit is completed from earth, resistance 147, contact of key 8, lead 170, wiper 111, working contact and armature 128, resting contact and armature 137, wiper 144, lead 166, armature 249 and its resting contact, winding of relay 204, winding of relay 203, battery. Relay 203 is marginally adjusted and does not energize unless dead earth is connected to lead 166 but relay 204 energizes at this 40 time and at armature 219 completes a circuit as follows: earth, winding of relay 201, back contact and armature 208, armature 218 and its back contact, armature 219 and its front contact, back contact and armature 45 214, wiper 227 and first contact of the transfer switch, lead 263, relay 231 to battery.

Relays 201 and 231 energize in this circuit and relay 201 at armature 210 completes a circuit for relay 200 as follows: 50 earth, working contact and armature 223 of the operated relay 204, working contact and armature 210, winding of relay 200 to battery. Relay 200 operates, at armature 208 opens the circuit for relay 201 which 55 thereupon de-energizes, at armature 209 completes a locking circuit for itself and at armature 211 closes a circuit for the stepping magnet 245 of the transfer switch which is arranged to step on release. In the first 60 storage relay group, relay 231 upon energizing, at armature 235 completes a locking circuit for itself to the earthed lead 168 so that it does not release when its initial energizing circuit is opened at armature 208, 65 at armature 239 opens a circuit for the

release magnet 246 so that the transfer switch is not released when the switch steps off normal and the off normal contact 247 closes, and at armature 243 closes a point in a chain circuit the purpose of which will be described 70 fully hereinafter.

The operation of the digit key 8 also closes the following circuit: earth, operated spring of key 8, lead 171, wiper 110 and the contact with which it is in engagement, working contact and armature 127, resting contact and armature 136, wiper 143, lead 165, armature 247 and its resting contact, winding of relay 206, winding of relay 205 to battery. Relay 205 is marginally adjusted in the same 75 manner as relay 203 but as dead earth has been connected to the energizing lead, both relays 205 and 206 energize in series. Relay 206 upon energizing, at armature 224 prepares a circuit for relay 200 and at armature 221 closes a point in the circuit over the wiper 225, which circuit however is not completed owing to another point being opened at the back contact of armature 220. Relay 205 at the front contact of armature 220 80 completes a circuit as follows: earth, relay 201, resting contact and armature 208, armature 220 and its working contact, resting contact and armature 213, wiper 226, first contact of transfer switch, lead 262, relay 230 to battery. The operation of relays 200 and 201 which will be produced by relays 205 and 206 is the same as produced by the 85 operation of relay 204 which has already been described. Relay 230, upon energizing 90 at armature 242 closes another point in the chain circuit, at armature 238 opens another point in the auxiliary release circuit and at armature 234 locks itself up to the earthed lead 168, at the same time connecting earth 100 to the first contact in the bank of wiper 226.

It will be noted that as long as the operator holds the digit key 8 depressed, the circuit of relay 200 will be maintained over 110 its own locking contact 209 and contacts 223 and 224 in parallel. As soon, however, as the key is released, relay 200 deenergizes and at armature 211 opens the circuit of the stepping magnet 245 which thereupon 115 advances the wipers 225-228 inclusive into engagement with the second set of bank contacts.

When the operator presses the key 6 in accordance with the next digit, a circuit 120 is completed from earth, resistance 147, lead 171, wiper 110 and the contact with which it is in engagement, working contact and armature 127, resting contact and armature 136, wiper 143, lead 165, armature 247 and its 125 resting contact, relay 206, relay 205 to battery. Since relay 205 is marginally adjusted, relay 206 alone energizes in this circuit and a circuit is thereby completed from earth at relay 201, back contact and arma- 130

ture 208, armature 220 and its back contact, armature 221 and its front contact, back contact and armature 212, wiper 225 and the second contact in its bank to battery through relay 265 in the second digit storage set.

At the same time a circuit is completed from resistance earth over the springs of the 6th digit key, lead 170 and lead 166 for relays 203 and 204, in consequence of which relay 204 energizes and completes a circuit over wiper 227 for relay 266. Clearly the operation of relays 200 and 201 will be the same in this case as has been previously described and when the digit key 6 is released, the transfer switch will be stepped on so that the wipers engage with the third set of contacts.

When the operator presses the digit key 4 for the next digit, a circuit is completed from earth, resistance 147, spring of key 4, lead 169, wiper 112, working contact and armature 130, resting contact and armature 138, wiper 145, lead 167, armature 250 and its resting contact to relay 202. A branch of this circuit also extends through resistance 251 to the relay 260, but relay 260 is adjusted so that it will not energize in series with both resistances 147 and 251. Relay 202 is energized, however, and at its contact 217 completes the usual circuit for relay 201 which will extend over back contact and armature 215, wiper 228 and the third contact of its bank to relay 267.

The circuit changes which take place in setting up the remaining digits will be readily understood from what has already been said, the general operation being that one or more of the relays 202-206 is operated and in consequence of this, circuits are completed over the wipers of the transfer switch for one or more of the relays in the appropriate storage sets. Relay 200 always remains energized as long as a digit key is depressed and when the key is released it de-energizes and brings about the advancement of the switch wipers into engagement with the succeeding set of bank contacts.

When the operator has set up the complete number she will press the start key 150. The effect of this is twofold: In the first place a circuit is completed for the driving magnet 123 which thereupon operates to step the wipers 110-113 inclusive, of the outlet finder one step so as to associate the key set with another outlet. In the second place a circuit is completed for the start relay 151, which thereupon energizes and closes its contacts 152, 153, 154 and 155. In any one case, however, only one of these contacts can be usefully operative; in the present case, a circuit is completed from battery, resistance 156, armature 155 and its working contact, winding of relay 121, resistance 141, armature 132 and its working contact, working contact and armature 131 to earth. Relay

121 is provided with a light armature 169¹ which is operated alone when the relay is energized in series with resistance 141 and by shunting armature 155 serves to maintain the battery connection after the start key 150 has been released and the start relay 151 deenergized.

It has been assumed in the foregoing that the A operator in the originating manual exchange has not yet plugged in on the trunk line assigned to her when the B operator presses her start key. An examination of the circuits will show, however, that it is immaterial whether the A operator plugs in or the B operator presses her start key first and that the sending of impulses will commence when both these actions have taken place irrespective of which preceded the other. The A and B operators may thus work independently in completing the connection and no loss of time is occasioned by one having to wait for the other.

Suppose therefore that the operations described above have taken place and the A operator now plugs in. A circuit is thereby completed across leads 1 and 2 for both windings of relay 21 which is accordingly energized. Upon operating, relay 21 at its armature 22 completes a circuit for the trunk busy lamp 24, which thereupon becomes lighted so as to notify to the tandem B operator that the A operator has plugged in. A circuit is also completed at contact 22 for the polarizing winding of relay 23 and over the normally closed spring 25 of the busy key for the relay 20. Relay 20 thereupon operates, at its armatures 39 and 40 closes points in the speaking leads and at its armatures 28, 29, 30, 31 prepares circuits for starting the sending of impulses. In any one particular case however, only one of these circuits can be operative and since the first outlet is being used, a circuit may now be traced from earth, armature 131 and its working contact, normally closed spring 117 of the sender disconnect key, lead 103, working contact and armature 17, working contact and armature 28, lead 104, winding of relay 121, working contact and armature 169¹, resistance 156 to battery. Resistance 141 is therefore short circuited and relay 121 consequently energizes fully, thereby operating its armatures 136, 137, 138, 139 and 140. At armatures 136, 137 and 138 the leads to the wipers 143, 144 and 145 are disconnected from the bank contacts of the outlet finder and are connected to the leads 107, 105 and 104 respectively. At armature 139, the holding circuit is prepared and at armature 140 the circuit for relay 119 and for the assignment lamp 27 is broken; the assignment lamp therefore goes out and relay 119 commences to de-energize. The connection of dead earth from lead 104 over armature 138 to lead 167 brings about the ener-

gization of relay 260 which energizes quickly and opens its contact 250 before the relay 202 has had time to operate. The relay 260 at armatures 247 and 249 disconnects the leads 165 and 166 from relays 206 and 204 respectively and connects them through to the impulsing contacts 269 and 270. At armature 248, a circuit is prepared for the relay 207, at armature 268 earth at armature 259 is connected to the holding lead 168 and at armature 252 a circuit is completed for relay 253. It should be understood that relay 119 is slow to release so that the earth connection at its armature 131 may be replaced by earth at armature 259 without any discontinuity.

Relay 253, upon operating, at armature 254 completes a circuit for the lower winding of relay 256 and at armature 255 completes a circuit for the release magnet 246 of the transfer switch over the operated off normal contact 247. The transfer switch is thereupon released, the circuit of release magnet 246 being opened at off normal contact 247 when the switch reaches normal position. When this occurs, a circuit is completed from earth at off normal contact 247, working contact and armature 248, winding of relay 207 to battery. Relay 207 operates, at armature 271 completes a locking circuit for itself independently of the off normal contact, at armatures 212-215, inclusive, disconnects the wipers of the transfer switch from the contacts of relays 202-206 and connects them to the converting relays 272, 273, 274 and 275 and at armature 216 completes a circuit for the impulsing relay 280. Relay 256 is a two-step relay similar to relay 121 and has a lightly adjusted armature 257 which is operated when the relay is energized over one winding only and serves to connect earth to the other terminal so that the upper winding is for the present short circuited.

As soon as relay 207 energizes a circuit is completed from earth, armature 259 and its resting contact, working contact and armature 268, working contact and armature 234, first contact in the bank of wiper 226 and said wiper, armature 213 and its working contact, relay 273 to battery, and a similar circuit may be traced over the operated contact 235 of relay 231 for relay 274. Relays 273 and 274 therefore energize and at their contacts 277 and 278 open the energizing circuit of relay 253. This latter therefore releases and at contact 254 removes the short circuit from the upper winding of relay 256 which thereupon operates all its armatures. At armature 258 it breaks the connection to the middle point of its winding and at armature 259 removes one earth connection from the lead 168. As, however, earth has already been replaced at the normally closed contacts controlled by armature 254, the oper-

ated relays are held up and the opening of contact 259 has no immediate effect.

Relay 273 also operates its armatures 281 and 282 and relay 274 operates its armatures 283, 284 and 285; a circuit is thereby completed from earth, armature 286 and its resting contact, armature 282 and its working contact, armature 284 and its working contact to the contact in the lower bank of the impulse control switch corresponding to the digit 8.

Since the circuit for the impulsing relay 280 was completed at armature 216 when relay 207 energized, relay 280 commences to energize intermittently under the control of the interrupter 287 which is driven at a steady speed and arranged to produce about 10 interruptions per second. When relay 280 energizes, it closes its contact 301, whereby the driving magnet 293 is energized and opens its contact 270; since, however, this is shunted by contact 269 no effect is produced at this time. Upon the following de-energization of relay 280, contact 301 is opened whereupon driving magnet 293 de-energizes and moves the wipers 289 and 290 one step. Wiper 289 then engages an earthed contact so that a circuit is completed for relay 292. Relay 292, upon energizing, at armature 269 places the impulsing circuit under the sole control of armature 270, at armature 299 prepares a circuit for the stepping magnet 245 of the transfer switch and at armature 300 prepares a locking circuit for relay 291.

When relay 280 next energizes it opens its contact 270 thereby interrupting the bridge across the outgoing trunk line which bridge may be traced as follows: from the upper talking conductor 37 through the normally closed contacts controlled by relays 18, 12 and 11, working contact and armature 14, lead 105, working contact and armature 137, wiper 144, lead 166, armature 249 and its working contact, armature 270 and its resting contact, working contact and armature 247, lead 165, wiper 143, armature 136 and its working contact, lead 107, armature 18 and its working contact, normally closed springs controlled by relays 11, 12 and 13 to lead 38; consequently an impulse is sent out over the trunk line to the distant selector. When the relay 280 again de-energizes, the wipers 289 and 290 are advanced another step and upon the next energization a further impulse is sent out over the trunk line. Relay 280 then continues to energize and de-energize under the control of interrupter 287 until the wiper 290 reaches the contact in its bank which was earthed over the armatures of the operated converting relays 273 and 274.

When this occurs, a circuit is completed from earth, armature 286 and its resting contact, armature 282 and its working contact,

tact, armature 284 and its working contact, contact in the upper bank of the impulse control switch, wiper 290, through the winding of relay 291 to battery, and in parallel 5 with this by way of armature 296 and its resting contact, armature 299 and its working contact to stepping magnet 245 of the transfer switch. Relay 291, upon operating, at armature 296 opens the circuit of the 10 stepping magnet 245 but not before it has had time to operate, at armature 288 opens the circuit of the impulsing relay 280, at armature 298 completes a locking circuit for itself and at armature 297 closes a circuit 15 over the interrupter contact 295 for securing the automatic return of the switch to its home position, since driving magnet 293 now continues to receive current over wiper 289 until the latter engages the dead 20 contact 294. When this occurs the circuit for relay 292 is opened and it thereupon releases, at its armature 300 opening the circuit of relay 291 which thereupon releases 25 also. Both these relays are, however, made slow to release so that an interval of time is introduced sufficient to allow of the automatic hunting operation of the selector which has just been operated.

When relay 291 at length de-energizes, 30 the circuit for the impulsing relay 280 is again completed at armature 288 and a further series of impulses is initiated. Now, however, the wipers of the transfer switch have been moved into second position and 35 since relays 265 and 266 of the second storage set have been operated relays 272 and 274 of the converting relay set will be energized. Consequently the contact corresponding to the digit 6 will now be earthed in the 40 bank of wiper 290 by way of armature 286 and its working contact, armature 281 and its resting contact and armature 283 and its working contact. The transmission of the 45 second series of impulses now proceeds as before under the control of the interrupter 287, the switch taking one idle step before relay 292 is energized and relay 291 operating and stopping the further transmission of impulses when wiper 290 engages with the earthed contact. The switch is then 50 restored automatically to its home position as before and is thus in readiness to transmit the third series of impulses under the control of the transfer switch which is now in its third position.

The transmission of the remaining digits 45321 will then take place in a manner which will be readily followed from the description that has already been given, the transfer 55 switch being advanced one step at the end of each series of impulses so as to be in a condition to control the succeeding series.

When the transfer switch arrives at the 8th position, wiper 225 will encounter a 60 permanently earthed contact and conse-

quently relay 272 will be energized to control the sending of a further train of one impulse which is additional to the number set up by the B operator. This impulse is employed in case the call is going to a call 70 indicator position to indicate to the operator there that the call she is dealing with has come from the mechanical tandem exchange and not direct from an automatic subscriber. In case the call is going direct to automatic 75 switches, this extra impulse will have no deleterious effect but will simply be absorbed. It is, however, by no means essential to the working of the system and in many cases it 80 may be thought desirable to omit it altogether.

After the sending of the special impulse, the transfer switch will be stepped on into its ninth position. Since, however, the ninth 85 set of contacts are not wired, no circuits will be completed for any of the relays 272-275 inclusive and they will therefore all de-energize. A circuit is thereupon completed over the back contacts of these relays for the relay 253 which operates and at its contact 255 completes a circuit for release magnet 246 and at its contact 254 removes the locking earth which is holding up all the operated apparatus. The transfer switch 90 therefore returns to normal and in consequence of this removal of earth, all the operated storage relays are released and also the relays 260 and 256. The release of the relay 260 breaks the circuits for the relays 207 and 253 at armatures 248 and 252 respectively 100 and the de-energization of relay 207 opens contact 216 so that the sending of impulses ceases. Relay 121 in the sender selector and relay 10 in the trunk circuit are also released and the sender guard lamp 164 is extinguished to indicate to the operator that sending has finished. Both the outlet and the particular sender used are now idle and 105 available for use in setting up other calls. The release of relay 10 completes the trunk 110 circuit at the normally closed contacts controlled by armatures 14 and 18 and the wanted subscriber, if idle, will be rung automatically in the usual manner unless the connection is to a call indicator position. When 115 the called man replies, the flow of current over the line will be reversed at the back bridge relay of the connector according to usual practice and will then be in a direction to operate polarized relay 23. Relay 23, 120 upon energizing, closes its contact 34 which substitutes the choke coil 33 in place of the high resistance upper winding of relay 21 so that the A operator in the originating 125 manual exchange is given answering supervision. Relay 21 will remain energized, however, until the A operator pulls down the connection upon the calling man hanging up, whereupon the lamp 24 will be extinguished and the tandem operator will know that the 130

junction line is idle and may be used for another call.

It will be advisable at this point to describe some of the arrangements provided for dealing with special conditions that may arise. Suppose in the first place that the operator has made a mistake in setting up the number but discovers it before she has pressed her start key. In this case she will operate the cancel key 149 individual to her position, the effect of which is to complete a circuit by way of armature 158 and its back contact for relay 159. Relay 159, upon operating, at armature 160 completes a circuit for relay 157 which thereupon operates in turn and at armature 158 opens the circuit of relay 159 and completes a locking circuit for itself dependent upon the key 149. Relay 159, being sluggish, de-energizes slowly and it is thus arranged that relay 159 will always operate its contacts for the same length of time however long the key 149 is kept pressed. Relay 159 at its contact 161 and similar contacts associated with the other outlets removes earth at armature 131 from wiper 146 and lead 168 so that the storage relay sets which have been operated for the digits already set up are released. When the relays 229-232 inclusive, of the first storage set de-energize, they complete a circuit from earth at off normal contact 247 in operated position over back contacts and armatures 237, 238, 239 and 240 for the release magnet 246 of the transfer switch; this switch is thus restored to normal in readiness to receive the correct first digit. The operator may then immediately set up the proper number and the sequence of operations will be as described above.

In case, however, the operator has pressed her start key and the sending of impulses has actually commenced before she discovers her error, it will be necessary to operate the busy or cancel key associated with the junction line which has been used. The effect of this is to open the circuit of relay 20 at spring 25 and the locking circuit of relay 10 at spring 26 whereupon both these relays de-energize. The de-energization of relay 20 opens the contacts 39 and 40 whereby the loop across the outgoing trunk is opened and the switches which have been operated are released. The opening of contact 28 removes from lead 167 the locking earth at the normally closed springs controlled by armature 254 in consequence of which relay 260 de-energizes and the release of all the operated apparatus in the set of impulse sending equipment takes place as previously described. It will then be necessary for the operator to start the setting up operation from the beginning, that is to say, it will be again necessary to press the assignment key and a different outlet and impulse

sender will be used from these which were previously employed. There is clearly no necessity to notify the A operator as the same junction line is used again.

Should the junction line be out of order and therefore not available for use, the operator will press the busy key associated with that line. In this case the only effective operation will be the completion of the circuit for the busy lamp 35 at springs 36, so that the operator is notified that the line must not be used. Inspection of Fig. 2 will show however, that should the operator assign the line in error it will be impossible for an impulse sender to be associated with it permanently and the lamp 27 will not glow steadily.

In case one of the outlets should be out of order, it will be necessary to operate the associated sender disconnect key. At the left hand springs of this key the energizing circuit for relay 120 is opened at spring 114 and at spring 115 earth is connected to the corresponding contact in the outlet finder so as to prevent this particular outlet being taken into use. At the right hand spring of the key a circuit is completed for the sender guard lamp 164 at the spring 116 and at spring 117 the energizing circuit for the relay 10 is opened.

The case when all the senders accessible to a sender selector are busy is taken care of by a chain circuit extending over one or more of the contacts 241, 242, 243, 244 in parallel and by way of lead 199 over one or more of similar contacts on the first storage relay set of the other impulse senders in the group to earth. When all the impulse senders are in use therefore a circuit is completed for relay 118 which upon operating at armature 112 connects earth to lead 170, at armature 121' opens the energizing circuit of relay 120 and at the front contact of this armature connects earth to the contact corresponding to this outlet in the bank of the outlet finder. One effect of the connection of earth to the contact with which wiper 113 is in engagement is to complete a circuit for relays 109 and 108. Relay 109 energizes and its armature 126 opens a point in a circuit for the driving magnet 123 and relay 108 also energizes a short while after and at armature 125 closes another point in this circuit which consequently never becomes operative. The earth connection through relay 109, which is of very low resistance, also extends over lead 100, armature 19 and its resting contact, chain of similar contacts on other assignment relays, armature 9 and its resting contact, lead 101, interrupter contact 124 to driving magnet 123. The driving magnet 123 therefore operates and advances the switch wipers one step into engagement with the next set of contacts. In case all the senders accessible

by way of this outlet are also busy, there will be earth on the contact with which wiper 113 is now in engagement and the switch will continue to hunt until an idle outlet is found over which the connection can be completed.

It might happen in some cases that the outlet which has been preselected has access to only one idle sender and that while the 10 associated sender selector is hunting for this sender it is taken into use from some other operator's position. It is clear that unless special provision were made the sender selector would continue to hunt until an 15 impulse sender became free and unnecessary waste of time and wear of the switch would be occasioned. In this case also therefore it is necessary for the outlet finder to step on to find a new outlet but the circuit 20 traced above is no longer operative since it is open at one of the chain contacts; however this condition is taken care of by relay 109. When the assignment key is 25 pressed, relays 108 and 109 are energized as previously described in series with relay 120 and the sender selector commences to hunt. When now all the senders in the 30 group become busy, relay 118 operates and substitutes an earth connection at armature 131 for the connection to battery through relay 120. Relay 109 is thereupon short circuited and at its armature 126 completes a circuit from earth, front contact and armature 122 of relay 118, armature 35 126 and its back contact, armature 125 and its front contact, interrupter contact 124 to driving magnet 123. The outlet finder is thus automatically stepped on to find a 40 free outlet and unnecessary hunting of the sender selector and waste of the operator's time are avoided.

Referring now more particularly to Figures 5, 6 and 7 these show a modification of the arrangement illustrated in Figs. 2, 3 and 4. The chief difference between the two arrangements is that in Figs. 5, 6 and 7 the outlet finder and sender selector switches have five wipers and in consequence it is possible to dispense with the 50 converting relays which were connected to the wipers of the sender selectors and to operate the storage relays direct. In addition various small improvements have been incorporated, such as the provision of 55 flashing signals to indicate to the operator the progress of the connection and an arrangement for obviating the possibility of two operators seizing the same set of 60 impulse sending equipment. These additional features will be more fully understood from the following detailed description of the operation of the apparatus.

As before the B operator is informed over an order wire of the required number 65 and she then assigns an idle junction line,

for instance that comprising conductors 302 and 303. At the same time she presses the corresponding assignment key 304, whereupon the assignment relay 305 is energized and operates its contacts 306, 70 307, 308, 309 and 310. At armatures 306-309 inclusive, circuits are prepared for the trunk connecting relays 312, 313, 314 and 315. It will be assumed in this case also that the first outlet is the one which will be 75 used and consequently the only armature that performs any useful function is armature 306 which prepares a circuit for relay 312. At armature 310, earth is connected by way of a chain of contacts such as armature 311 on all the assignment relays to lead 400 which extends to equipment individual to the position and common to all the outlets.

The effect of this earth connection is to 85 energize the relays 408, 409, 410 and 420, the circuits for the two last extending from earth on lead 400, winding of relay 410, wiper 460 and the contact with which it is in engagement, normally closed spring 90 462 of the sender disconnect key, armature 434 and its back contact, relay 420 to battery. Relay 408 operates its armature 452 and 453 thereby closing contacts for a purpose which will be fully described hereafter. 95 Relays 409 and 410 at contacts 465 and 466 control the circuit of the driving magnet 467. As however, relay 409 is slightly slow to pull up, contact 466 will always be 100 opened before contact 465 closes and a circuit will in the normal course of operation never be completed for magnet 467, even should earth be connected to lead 469 which will not in general be the case. Relay 420 upon energizing, at armature 432 completes 105 a circuit for cut off relay 419 and driving magnet 445 in series which circuit may be traced as follows: earth, resting contact and armature 492, armature 456 and its resting contact, wiper 455 and the contact with which it is in engagement, armature 452 and its working contact, armature 432 and its working contact, winding of relay 419, interrupted contact 446, driving magnet 445 to battery. Relay 420 also at armature 433 connects the test wiper 474 of the sender selector by way of resting contact and armature 451 and armature 431 and its resting contact to the junction of relay 419 and driving magnet 445 in the above 110 circuit. Consequently if there is an earth on the contact with which wiper 474 is in engagement, relay 419 will be short circuited and the switch will commence to hunt in the usual manner until wiper 474 engages 115 with a contact which is not earthed. 120

When this occurs, relay 419 will energize in series with driving magnet 445, which latter, however, does not now receive enough current to energize it. Relay 419 130

upon operating, at armature 430 completes a locking circuit for itself to the earth on back contact of armature 444, at armature 431 disconnects the driving magnet 445 and places earth on test wiper 474 and at armature 429 completes a circuit for relay 418. Relay 418 upon operating, at armatures 424, 425 and 426 connects the wipers 456, 457 and 458 through to the wipers 470, 471, 472 respectively, wiper 459 having previously been connected through at armature 428 by the operation of relay 419. At armatures 475 and 427, battery and earth respectively are connected to leads 402 and 403 extending to the trunk circuit, the earth connection to lead 403 being over the normally closed spring 464 of the sender disconnect key. A branch circuit from this spring also extends to the sender guard lamp 476 which therefore lights and indicates that the corresponding outlet is in use.

The effect of the connection of battery and earth to the leads 402 and 403 is to complete an energizing circuit for the trunk connecting relay 312 which circuit may be traced from the battery connection on lead 402 by way of the normally closed contacts controlled by armature 320, winding of relay 312 and armature 305 and its working contact to earth on lead 403. Relay 312 therefore operates, at its armatures 316 and 317 connects the outgoing trunk conductors 336 and 337 to the impulsing leads 405 and 407, and at armature 318 completes a circuit from the normal battery connection on lead 406 by way of resting contact and armature 439 to the assignment lamp 322, armature 332 and its resting contact and flashing interrupter 333 so that the assignment lamp 322 commences to flash. Relay 312 also at armature 319 prepares an energizing circuit for relay 338, at armature 320 opens its initial energizing circuit and completes a locking circuit for itself by way of the normally closed spring 326 of the busy or cancel key and at armature 321 shunts armature 306 so that its own circuit is not interrupted when relay 305 deenergizes upon the release of the assignment key 304. The operator keeps the assignment key pressed until the lamp 332 lights, whereupon she knows that the outlet finder and sender selector switches are functioning correctly and that her key set is now connected to an idle set of impulse sending equipment.

The apparatus is now in readiness for registering the wanted number as set up upon the key set. Suppose that the numerical equivalent of the wanted number is 8765432. When the key 8 is pressed, a circuit is completed from earth, operated spring of digit key 8, lead 480, wiper 457, and the contact with which it is in engagement, working contact and armature 425, resting contact and armature 440, wiper 471,

lead 501, armature 526 and its resting contact, resting contact and armature 537, wiper 545 and the first contact in the bank, lead 548, armature 519 and its resting contact, upper winding of relay 508, normally closed contact controlled by armature 520, resting contact and armature 532, relay 538 to battery. Relay 508 partially energizes in this circuit and operates its lightly adjusted armature 549 whereby the other terminal of the lower winding is connected to the earthed lead 504. Since, however, the lower winding is now short circuited by an earth connection to both its terminals, there is no further operation of relay 508 at this time. Relay 538, however, operates fully; at armature 539 completes a circuit for relay 550, at armature 540 opens a point in the circuit of the stepping magnet 551 of the transfer switch and at armature 541 opens a point in the circuit of relay 552. Relay 550 energizes when its circuit is completed and at armature 543 prepares a circuit for the stepping magnet 551. A similar circuit is also completed from the other operated spring of the digit key 8, which circuit extends over lead 481, wiper 458 and the contact with which it is in engagement, working contact and armature 426, resting contact and armature 441, wiper 472, lead 502, armature 527 and its resting contact, resting contact and armature 533, wiper 546 of the transfer switch in first position, lead 553, armature 554 and its resting contact, upper winding of relay 509, normally closed springs controlled by armature 555, resting contact and armature 532, and through the winding of relay 538 to battery. Relay 509 accordingly operates its armature 556 which is adjusted similarly to armature 549 but none of its other armatures which are more stiffly adjusted.

When the digit key is released, earth is removed from the middle point of the windings of relays 508 and 509 and these relays accordingly both energize fully through their two windings in series while relay 538 is de-energized. Relay 508 upon operating, at armature 512 closes a point in a chain circuit for a purpose which will be explained hereafter, at armature 516 opens a point in the circuit of release magnet 557 of the transfer switch, at armature 520 opens its initial energizing circuit and completes a locking circuit for itself and at armature 519 connects earth from lead 504 to the corresponding contact in the bank of wiper 545. The operation of armatures 513, 517, 555, and 554 of relay 509 produces a similar result.

When relay 538 deenergizes, armature 540 engages with its resting contact and since relay 550 is made slightly slow by providing it with a short circuited winding, a circuit is now completed which extends from earth,

resting contact and armature 540, stepping magnet 551 to battery; the transfer switch is thus moved on one step into engagement with its second set of contacts.

5 The operator will now press the key for the second digit 7 whereupon a circuit is completed from earth, operated spring of digit key 7, winding of relay 482 to battery. Relay 482 at its armature 485 completes a circuit as follows: earth, working contact and armature 485, wiper 456 and the contact on which it is standing, working contact and armature 424, wiper 470, lead 500, armature 525 and its resting contact, resting contact 10 and armature 536, wiper 544 in second position, over resting contact of relay 558 similar to contacts 519 and 554, upper winding of relay 558, normally closed springs controlled by an armature similar to armature 520, 15 resting contact and armature 532, relay 538 to battery. Relay 558 thereupon operates its light armature and when the key is released operates fully, producing results similar to those described in connection with the 20 first set of storage relays. Relay 538 energizes as before and jointly with relay 550 controls the stepping on of the transfer switch when the digit key 7 is released.

A circuit is also completed by the operation 30 of key 7 from earth, operated spring of key 7, lead 479, wiper 459, working contact and armature 428, resting contact and armature 442, wiper 473, lead 503, armature 528 and its resting contact, resting contact and armature 534, wiper 547 and the second contact in its bank through the upper winding 35 of relay 559 and relay 538 to battery. A branch of this circuit extends over resting contact and armature 541 to the winding of relay 552. As however, relay 552 is slightly slow to pull up and its circuit is at once 40 opened by the operation of relay 538 it does not energize at this time.

As a result of the pressing of the digit key 45 7 for the second digit therefore, relays 558 and 559 have been locked up and earth has been connected to the second contacts in the banks of wipers 544 and 547. As previously stated the transfer switch is stepped on 50 when the key 7 is released and moves into position 3 so as to connect up the third storage relay set. The operation of setting up the remaining digits will readily be followed from what has already been described and need not be traced in detail.

After the seventh digit has been sent, however, the transfer switch will be stepped on into the eighth position in the usual manner but when relay 550 deenergizes a circuit 60 may be traced as follows: earth, resting contact and armature 560, eighth contact in the bank of wiper 544 and said wiper, armature 536 and its resting contact, resting contact and armature 525, lead 500, wiper 470, 65 armature 424 and its working contact, wiper

456, armature 485 and its resting contact, winding of relay 486 to battery. Relay 486 thereupon at once energizes and at its armature 488 completes a circuit for stepping magnet 467 and at its armature 487 70 completes a circuit for start relay 489. Stepping magnet 467 then moves the wipers of the outlet finder one step into engagement with the next outlet whereupon the circuit for relay 486 is opened and the relay deenergizes. Start relay 489 energizes when its circuit is completed and at its armature 490 completes a circuit for relay 422. It will be noted that relay 489 has a pair of contacts for each outlet but clearly since 75 only one outlet can be used at a time, only one of these pairs of contacts will in each case perform any useful function. Relay 422 upon operating at armature 438 completes a locking circuit for itself independent of armature 490, at armature 437 removes the battery connection from lead 402 so as to prevent any other trunk relays associated with this outlet from energizing when the next assignment key is pressed, 80 and at armature 436 prepares a circuit for relay 423.

It should be noted that with the arrangement described, if the operator sends the full seven digits which is the maximum for 85 which the arrangement is designed (though obviously comparatively slight alteration is necessary to enable a larger number to be dealt with) no special operation on her part is necessary in order to initiate the actual 90 sending of impulses, since the relay 486 performs the same function as the start key 483. If, however, a less number of digits is being sent, all the required operations can be made to take place without any alterations to the 95 apparatus, the only difference being that it will now be necessary for the operator to press the start key when she has set up all the required digits, in the same manner as was done in every case in the arrangement 100 described in Figs. 2, 3 and 4.

For the sake of convenience it will be again assumed, as in describing the previous arrangement, that the pressing of the start key or equivalent automatic operation takes 115 place before the A operator has plugged in. When she does so a supervisory circuit is completed over the lower talking conductor 303 and the normally closed spring 348 of the emergency order wire key for relay 339. 120 Relay 339, upon operating, at its armature 340 completes a circuit for the polarizing winding of relay 342 and also a circuit for relay 338 which latter circuit extends as follows: earth, armature 340 and its working contact, normally closed spring 325 of the busy or cancel key, working contact and armature 319, relay 338 to battery. Relay 338, upon operating, at its armatures 334 125 and 335 closes points in the outgoing trunk 130

leads, at its armature 327 completes a locking circuit for itself, at its armature 332 substitutes a direct earth connection for the earth connection by way of the flashing interrupter 333 and at its armatures 328, 329, 330 and 331 prepares circuits for initiating the generation of impulses. As previously explained, only one of these circuits will be usefully operative at a time. In this case 10 the joint operation of armatures 332 and 341 completes a circuit for the trunk busy lamp 323 and the assignment lamp 322 so that the latter, which has previously been flashing under the control of the flashing interrupter 333, will now glow steadily. 15

In consequence of the operation of armature 328 a circuit may now be traced from earth, armature 427 and its working contact, normally closed spring 464 of the sender disconnect key, lead 403, working contact and armature 321, working contact and armature 328, lead 404, armature 436 and its working contact, winding of relay 423 to battery. Relay 423 therefore energizes and upon operating, at its armatures 25 440, 441 and 442 connects the wipers 471, 472 and 473 to the leads 407, 405 and 404 respectively. Furthermore at armature 439 it removes the battery connection from lead 406 so that the assignment lamp 322 is extinguished, at armature 443 prepares the holding circuit and at armature 444 opens the circuit for relay 419. Relay 419 slowly deenergizes and at armature 429 opens the 35 circuit for relay 418 which also slowly deenergizes.

The connection of earth to lead 503 by way of the resistance 495 completes a circuit by way of resting contact and armature 541 for relay 552. A branch of this circuit also 40 extends over armature 528 and its resting contact, resting contact and armature 534, to wiper 547, but since this wiper is in engagement with the eighth contact, which is 45 dead, clearly no effect can be produced. It may happen, however, if the operator is desirous of transmitting less than the maximum number of digits i. e. 7, that the wiper 547 would not be standing on the eighth 50 contact but on one which was connected to a relay of a storage set and obviously if this relay has not previously operated it must now do so. It is for this reason that the resistance 495 is inserted, relay 552, however, being arranged to operate in series 55 with this resistance. Relay 552 upon operating, at its armatures 525, 526, 527, and 528 disconnects the leads 500, 501, 502, 503 from the wipers 544, 545, 546 and 547 respectively, of the transfer switch, at armature 529 prepares a circuit for relays 530 and 531, at armature 561 places earth by way of armature 573 on the holding lead 504 and at armature 562 completes a circuit 60 for relay 567 by way of resting contacts

563, 564, 565, 566 of the converting relays 521, 522, 523, 524. Owing to relays 418 and 419 being slow to release, earth at armature 573 is connected to holding lead 504 before it is removed at armature 427 even though 70 relay 552 is slightly slow to pull up.

Relay 567 upon operating, at armature 570 completes a circuit from earth, operated off normal spring 575, working contact and armature 570, release magnet 557 to battery, 75 whereupon the transfer switch is restored to normal. Relay 567 at armature 569 completes a circuit for the upper winding of relay 568 which is thereupon partially energized and operates its lightly adjusted armature 571. Earth is then connected to the other terminal of the upper winding of relay 568 so that this winding is for the present short circuited. As soon as the transfer switch reaches normal position, a 80 circuit is completed from earth, normally closed spring 574, working contact and armature 529, relay 531, relays 530 to battery. Relays 530 and 531 energize in series and the former at armature 532 opens the energizing 85 circuit for the storage relays so as to prevent any subsequent accidental operation and at armatures 533 and 534 connects wipers 546 and 547 to the converting relays 523 and 524. Relay 531 at its armature 535 90 completes a locking circuit for itself and relay 530, at its armature 542 closes a circuit for impulsing relay 578 and at armatures 536 and 537 connects wipers 544 and 545 through to the converting relays 521 and 95 522. Since the relays 508 and 509 of the first storage set have been operated, a circuit is now completed from armature 573 and its resting contact, armature 561 and 100 its working contact, working contact and armature 519, lead 548, first contact in the bank of wiper 545 and said wiper, armature 537 and its working contact, relay 522 to battery and a similar circuit may be traced over working contact and armature 554, lead 105 553, first contact in the bank of wiper 546 and said wiper, armature 533 and its working contact, relay 523 to battery.

The resulting operation of relays 522 and 110 523 opens the circuit of relay 567 at armatures 564 and 565 and relay 567 consequently deenergizes. A further earth is thereupon placed on the holding lead 504 at the normally closed contacts controlled by armature 569 and at the same time earth is removed from the middle point of the winding of relay 568. This relay thereupon operates fully, at armature 572 breaks the connection of the middle point of its winding and at armature 573 removes the parallel earth from 120 the holding lead 504.

The sending of impulses now commences and will proceed as described in connection with Fig. 4. Relay 578 is intermittently 125 energized and deenergized and accordingly 130

intermittently operates its armature 577. This armature has sole control of the impulsive circuit after armature 576 is operated when the impulse control switch takes its first step and thus produces corresponding interruptions in the circuits of the line relays of the various selector and connector switches.

In this case also provision is made for sending a special impulse to a call indicator position after the seven digits set up by the B operator have been transmitted. This is brought about by the earth connection over resting contact and armature 560 to the eighth contact in the bank of wiper 544 and the operation is similar to that described in the previous case.

The release of the various operated relays after all the digits have been sent also takes place in a manner similar to that described before, the holding earth being removed from the lead 504 at the normally closed springs controlled by armature 569 when relay 567 is again operated due to the deenergization of all the converting relays 521, 522, 523, 524.

In case the operator makes a mistake in setting up the wanted number and discovers it before the complete number has been set up, that is, before the operations corresponding to the pressing of the start key have taken place, she is enabled to cancel the digit already set up by pressing the cancel key 484. This brings about the momentary operation of relay 448 and the operation of relay 447 as long as the key is kept pressed. Relay 448 upon energizing, at its armature 451 removes earth from the holding lead 504 thereby releasing all the operated storage relays, and at its armature 456 removes earth from wiper 455 so as to prevent another operator from seizing this set of impulse sending equipment during the momentary removal of earth from test wiper 474. In case the sending of impulses has actually commenced she will as in the previous arrangement, press the busy or cancel key associated with the trunk line which has been taken into use, the effect of this being to open the locking circuit for the relays 338 and 312, thereupon on the deenergization of relay 338, the locking earth for relay 552 is removed at armature 328 so that this relay deenergizes and releases all the operated apparatus in the set of impulse sending equipment as in the ordinary course. The operator will then press the assignment key 304 again whereupon another impulse sender set will be seized and the connection may be completed in the ordinary way.

The emergency order wire key is provided in order to enable the inter-exchange junction line to be used as an order wire in case of necessity. When the key is operated the

connections of conductors 302 and 303 to the trunk circuit relays are broken at springs 346 and 348 and these conductors are connected at springs 347 and 349 to the leads 351 and 352 which can be extended to the operator's head set. At spring 350 a circuit is completed for the trunk busy lamp 323 which is thus lighted to indicate to the operator that the trunk line is not available for use.

It may be desirable at this point to explain the precise nature and operation of the lamp signals which are provided to indicate to the operator the progress of the connection. As has already been explained, the operator holds the assignment key pressed until the assignment lamp 322 lights. If the A operator has not already plugged in, the lamp 322 will glow intermittently under the control of the flashing interrupter 333, and will continue to flash until the A operator does plug in, after which it will glow steadily until the sending of impulses commences. At the same time the sender guard lamp 476 will light and glow steadily to indicate that an outlet is in use. As has been pointed out if the A operator is a trifle late in plugging in, this operation will control the starting of the sending of impulses and consequently in this case the lamp 322 will continue to flash until it is extinguished.

The trunk busy lamp 323 will always be lighted when the A operator plugs in; in case the B operator should not yet have pressed her assignment key, the lamp will flash until the key is pressed and an idle impulse sender is found whereupon it will glow steadily and continue to do so until the connection is taken down. By means of these lamp signals the operator is kept fully informed of the progress of the connection except that she is not given answering supervision when the calling subscriber replies as this is clearly unnecessary. The sender guard lamp 476 will remain lighted as long as the particular outlet is in use or the sender disconnect key is operated. This is similar to those provided in the previous arrangement and when operated lights the sender guard lamp and prevents the particular outlet from being taken into use. The arrangement of relays 409, 410 and 421 is the same as that previously described and has for function the preselection of an outlet having access to an idle impulse sender and the moving on of the outlet finder in case all the senders in a particular group should become busy after the assignment key has been pressed. The chain circuit for energizing relay 421 extends over contacts 511, 512, 513 and 514 in parallel and over similar contacts on other first storage relay sets in the group to earth.

A description may now be given of the apparatus shown in the lower part of Fig. 139

6, the object of which is to obviate the possibility of two operators seizing the same impulse sender at the same time. The relays such as 408 are individual to each operator's 5 position and each is connected to the lead corresponding to lead 400 so that it will energize whenever any assignment key in the position is pressed. Relay 408 controls two armatures 452 and 453 in chain circuits 10 which include contacts controlled by the relays similar to 408 associated with all the other positions having access to the same group of impulse senders. The former of 15 these circuits comprises a closed circuit extending through the armatures and back contacts, while the armatures are also connected to appropriate contacts in the bank of wiper 455. The front contacts of these armatures extend to armatures such as 432 and are 20 thus included in the energizing circuits of the cut-off relays such as 419. It will be remembered that the circuit for relay 419 was traced from earth at resting contact and armature 492, chain of similar contacts on 25 other cancelling relays, armature 456 and its resting contact, wiper 455 and the contact with which it is in engagement, armature 452 and its working contact to relay 419. It will be seen that if only one relay such 30 as 408 is operated at a time and the wiper 455 is in a different position from that shown, a circuit for relay 419 will still be completed over the armatures such as 452 and their back contacts. When, however, 35 there is more than one relay 408 operated at a time in which case wiper 455 will be rotating, as about to be explained, circuits for relays such as 419 will only be completed in turn as wiper 455 comes into engagement 40 with the contact connected to the armature controlled by the particular relay. By this means it is made certain that no two operators can possibly seize the same impulse 45 sender owing to their respective sender selectors coming to rest at the same instant on multiplied contacts. In order to arrange that the wiper 455 shall rotate when at least two operators press their assignment keys simultaneously but not otherwise the second 50 chain circuit, including contacts 453, 493 and 494 is made use of. It will be apparent from inspection of the drawing that as long as none or only one of the relays 408 is operated, a circuit will not be completed for the 55 driving magnet 491 of wiper 455 but as soon as two or more of these relays are operated, a circuit is completed and consequently the wiper 455 is started up. By this means unnecessary rotation of wiper 455 is avoided 60 and the life of the switch is correspondingly lengthened. The relays 408 will only be operated as long as the operator keeps her assignment key pressed and thus it is by no means unlikely that, even with a large 65 number of operators, only one may be press-

ing an assignment key at any particular instant. The earth connection to the wiper 455 is taken through additional contacts on the cancellation relays such as 448 in order that if an operator presses her cancel key 484 70 whereupon earth is momentarily removed from the multiple test contact in the bank of wiper 474, no other operator will be able to seize the impulse sender which has been taken into use and it can be used again for 75 setting up the proper number and the transmission of the required impulses.

It has been arranged both in the arrangement shown in Figs. 2, 3 and 4 and in the arrangement shown in Figs. 5, 6 and 7 that 80 the sending of impulses does not commence until the A operator plugs in, since this is in general desirable. It should be understood however, that this is not essential to the working of the arrangement and that by 85 eliminating the starting contacts on the relays 20 or 338 and substituting direct connections, the starting of the generation of impulses may be placed under the sole control of the B operator at the tandem exchange. 90

Having now particularly described and ascertained the nature of our said invention and in what manner the same is to be performed, we declare that what we claim is: 95

1. In a telephone system, a plurality of trunk lines, an assignment key individual to each of said trunk lines, a plurality of register senders, a plurality of operator's link circuits, an operator's key set, and means responsive to the operation of one of said assignment keys for connecting said key set to an idle link circuit and for connecting said idle circuit with the assigned trunk line and with an idle register sender. 100

2. In a telephone system, a plurality of trunk lines, a plurality of link circuits, a plurality of register senders, a key set, means including a forward hunting switch individual to said key set for connecting said key set with an idle one of said link circuits, operator-controlled means for connecting said idle link circuit with an idle trunk line, and a hunting switch for effecting a connection between the last named link circuit and an idle sender. 110

3. In a telephone system, a plurality of trunk lines, a plurality of link circuits, a plurality of register senders, a key set, a forward-hunting switch individual to said key set for connecting said key set with an idle one of said link circuits, and operator-controlled means for effecting a connection between said idle link circuit and an idle trunk line and for effecting a connection between said link circuit and an idle register sender. 120

4. In a telephone system, a plurality of trunk lines, a plurality of register senders, a plurality of link circuits, an operator's key set, means for connecting said key set with an 130

idle one of said link circuits, operator-controlled means for connecting the last named link circuit with an idle line and for connecting it with an idle register sender, and means for preventing the connection of said key set with an idle link circuit in case no sender is available for connection with such link circuit.

5. In a telephone system, a group of trunk lines, a plurality of link circuits, a plurality of register senders, an operator's key set, an automatic switch having wipers for connecting said key set to any idle one of said link circuits, a starting circuit including contacts individual to each of a plurality of said trunk lines and a wiper of said key-connecting switch, and switching apparatus controlled over said start circuit to connect the idle link circuit with which the key set is associated with one of said trunk lines and with an idle sender.

6. In a telephone system, a plurality of trunk lines, a plurality of link circuits, a plurality of register senders, a key set, means for connecting said key set with an idle link circuit and for connecting said link circuit with one of said trunk lines and with an idle one of said register senders, registering means in said register sender controlled by said key set to register a telephone number, means for starting the operation of the register sender to retransmit the registered number and means thereupon effective for associating said key set with another idle link circuit.

7. In a telephone system, a plurality of trunk lines, a plurality of link circuits, a plurality of register senders, a key set, means for connecting said key set with an idle link circuit and for connecting said link circuit with one of said trunk lines and with an idle register sender, separate registering devices in said register sender for recording the separate digits in a telephone number set up on said key set, a set of transfer relays in said register sender connected between the key set and the registering devices, and means for associating said transfer relays with a new register device each time a digit is registered.

8. In a telephone system, a plurality of trunk lines, a plurality of link circuits, a plurality of register senders, a key set, means for connecting said key set with an idle link circuit and for connecting said link circuit with one of said trunk lines and with an idle register sender, means in said register sender for registering digits set up on said key set, and a set of code transfer relays in said register sender interposed between the key set and the registering devices and responsive to one code of signals from said key set to transmit another code of signals to effect said registration.

65. 9. The combination, in a register sender

employing a plurality of registers and a sending device for transmitting a series of impulses under the control of each of said registers in turn, of a register-operating device, a step by step automatic switch having wipers for connecting said device with said registers successively, means for transmitting a distinctive impulse back over one of the wipers of said switch, and means associated with the sending apparatus responsive to said impulse to initiate the retransmission of the stored digits.

10. In a telephone system, a plurality of trunk lines, a plurality of link circuits, a plurality of register senders, a key set, means for connecting said key set with an idle link circuit and for connecting said link circuit with one of said trunk lines and with an idle register sender, registering means included in said register sender for storing up the digits set up on said key set, sending means in said register sender for retransmitting, over the trunk line connected with the link circuit, the digits stored up in the register sender, and means for automatically starting the operation of said sending apparatus responsive to the registration of the complete number.

11. In a telephone system, a plurality of trunk lines, a plurality of link circuits, a plurality of register senders, an operator's key set, means for connecting said key set with an idle link circuit, a relay switching device for connecting said idle link circuit with any one of said trunk lines, and a forward hunting switch for connecting the link circuit to an idle register sender.

12. In a telephone system, a plurality of register senders, a link circuit, an automatic switch having wipers for effecting a connection between said link circuit and an idle one of said register senders, means in said register sender for registering and retransmitting a telephone number, means in said link circuit for applying a holding potential through one of said wipers to maintain said register sender in operated condition, means for automatically removing said holding potential at the completion of the retransmission of a registered number, and operator-controlled means for removing said holding potential prior to said automatic removal.

13. In a telephone system, a plurality of trunk lines, a plurality of link circuits, a plurality of register senders, a key set, means for connecting said key set to an idle one of said link circuits, means for connecting the last named link circuit with one of said trunk lines and for connecting it with an idle register sender, means in said register sender for registering a number set up on said key set and for retransmitting through said link circuit and over said trunk line impulses corresponding to said number, means in said link circuit for maintaining the con-

nection between the link circuit and the register sender, means controlled over said trunk line for maintaining said connection, and means effective upon the initiation of 5 the sending operation for transferring the maintenance of said connection from the first maintaining means to the second maintaining means.

14. In a telephone system, a plurality of 10 trunk lines, a plurality of link circuits, a plurality of register senders, a key set, means for connecting said key set to an idle one of said link circuits, means for connecting the last named link circuit with one of 15 said trunk lines and for connecting it with an idle register sender, means in said register sender for registering a number set up on said key set and for retransmitting through 20 said link circuit and over said trunk line impulses corresponding to said number, means in said link circuit for maintaining the connection between the link circuit and the register sender, means controlled over 25 said trunk line for maintaining said connection, means effective upon the initiation 30 of the sending operation for transferring the maintenance of said connection from the first maintaining means to the second maintaining means, and means in said register 35 sender for bringing about the disconnection of said register sender and the link circuit responsive to the completion of the sending operation.

15. In a telephone system, a plurality of 40 trunk lines, a plurality of link circuits, a plurality of register senders, a key set, means for connecting said key set to an idle one of said link circuits, means for connecting the last named link circuit with one of said 45 trunk lines and for connecting it with an idle register sender, means in said register sender for registering a number set up on said key set and for retransmitting through 50 said link circuit and over said trunk line impulses corresponding to said number, means in said link circuit for maintaining the connection between the link circuit and the register sender, means controlled over 55 said trunk line for maintaining said connection, and means effective upon the initiation 60 of the sending operation for removing the control of the maintenance of the connection between the link circuit and the sender from the link circuit, and for placing such control with the calling line and with 65 the register sender jointly.

16. In a telephone system, a plurality of 70 trunk lines, a plurality of link circuits, a plurality of register senders, a key set, means for connecting said key set to an idle one of said link circuits, means for connecting the last named link circuit with one of 75 said trunk lines and for connecting it with an idle register sender, means in said register 80 sender for registering a number set up on

said key set and for retransmitting through 76 said link circuit and over said trunk line impulses corresponding to said number, means in said link circuit for maintaining the connection between the link circuit and the register sender, means controlled over 81 said trunk line for maintaining said connection, and operator-controlled means individual to the trunk line over which the impulses are being transmitted for breaking 85 the connection between the link circuit in use and the register sender.

17. In a telephone system, a plurality of hunting switches having multiplied bank contacts, means for causing said switches to hunt for idle contact sets, means for causing any one of said switches to seize any idle contact set found, means comprising a switching device for preventing simultaneous seizure of an idle contact set by two hunting switches, while permitting said switches to hunt simultaneously and means for operating said device only in case two or more of said switches are hunting simultaneously.

18. In a telephone system, a plurality of hunting switches having multiplied bank contacts, means for causing said hunting switches to hunt simultaneously for idle contact sets, a switching relay for each of 95 said switches, means for energizing the switching relay in any switch when said switch reaches an idle set of bank contacts, and means common to all said switching 100 relays and operated only in case two or more of said switches are simultaneously hunting whereby the initial energizing circuits are permitted to be closed only one at a time.

19. In a telephone system, a plurality of 105 hunting switches having multiplied bank contacts, means for causing said hunting switches to hunt simultaneously for idle contact sets, a switching relay for each of said switches, means for energizing the switching relay in any switch when said switch reaches an idle set of bank contacts, common means operated only in case two or more of said switches are simultaneously 110 hunting for permitting the initial energizing circuits of said switching relays to be closed only one at a time, and means effective in case only one switch is hunting for permitting the switching relay of such switch to 115 energize immediately upon an idle set of bank contacts being reached, regardless of the position of said common apparatus.

20. In a telephone system, a plurality of 120 hunting switches having multiplied bank contact sets, means for causing one or more of said switches to hunt for idle contact sets at the same time, a distributing switch for permitting said switches to seize idle contact sets only one at a time, and means for operating said distributing switch only 125 130

in case two or more of said switches are hunting simultaneously.

21. In an impulse transmitter, a counting switch for controlling the transmission of impulses, a set of permutational relays for controlling said counting switch, a plurality of sets of permutational storage relays, and a sequence switch operated after a digit is transmitted to associate the first mentioned set of permutational relays with another set of said permutational storage relays.

22. In a register sender, a plurality of sets of permutational storage relays, means for storing a telephone number on said relays, one digit per set of relays, a counting mechanism for counting each series of impulses transmitted by said sender, a set of permutational relays for controlling the operation of said counting device in accordance with the instant digit to be transmitted, and means for placing the last named set of permutational relays under the control of said storage relay sets successively, whereby the number stored on said relay set is retransmitted by said sender.

23. In a register sender including a counting switch for controlling the sending operation, a set of permutational relays for controlling said switch, a plurality of separately-operable registers, and means for successively associating said relays with said registers.

24. In a register sender, a sender including a counting switch, registering means divided into a plurality of sections, a set of permutational relays for controlling said counting switch, and means for associating said permutational relays with said register sections one after the other to secure a corresponding number of digit settings of said permutational relays.

25. In a register sender comprising registering means and sending means for registering and retransmitting a plurality of series of digit impulses, a set of relays for controlling the operation of said sending means, means for setting and resetting said relays a plurality of times under the control of said registering means to record a digit each time they are set, and means for operating the sending means each time said relays are set to retransmit the recorded digit.

26. In a register sender, a set of receiving relays, sets of storage devices, a set of sender control relays, a switching device, means for operating said switching device to successively associate said storage devices with said sets of receiving relays, and means for reoperating said switching device to successively associate said storage devices with said sender control relays.

27. In a register sender, a set of receiving relays, sets of storage devices, a set of sender control relays, means for successively con-

necting said storage devices with said receiving relays in order to set the storage devices and for then successively connecting the set storage devices with said sender control relays, and a set of common conductors over which said connections are established.

28. In a register sender, a set of receiving relays, sets of storage devices, a set of sender control relays, means for successively connecting said storage devices with said receiving relays in order to set the storage devices and for then successively connecting the set storage devices with said sender control relays, a set of common conductors over which said connections are established, said conductors being normally connected to said receiving relays, and a switching relay for transferring said conductors to said sender control relays.

29. In a register sender, a register setting device, an impulse transmitting mechanism including a counting device, a storage device individual to said counting device, a plurality of registers, a sequence switch, and means for operating said sequence switch to successively associate said registering devices with said register setting device, and for subsequently associating said registering devices with said storage device.

30. In a register sender, a set of common conductors, a plurality of sets of register controlling conductors, a register setting device, a sender controlling device, and means including said common conductors for associating said register setting device successively with said sets of register controlling conductors and for associating said sender controlling device with said register controlling conductor sets successively.

31. In a register sender, a set of permutational relays, a like number of conductors extending to said relays, respectively, means controlled over said conductors for energizing a certain combination of said relays, armature springs on said relays for locking the same energized and for placing a distinguishing potential on the conductor leading to each locked relay, and a like number of sender control relays subsequently controlled over said conductors by said distinguishing potentials.

32. In a telephone system, an operator's switchboard, a group of trunks at said switchboard, a plurality of register senders, a plurality of link circuits, means for extending a connection to one of said trunks, a control conductor individual to such trunk, means controlled over said conductor for connecting said trunk with an idle register sender through the medium of one of said link circuits, a train of automatic switches, a key set at said switchboard, a step by step automatic switch individual to said key set, means including said individual switch for connecting said key set with the last men-

tioned link circuit, means responsive to the operation of said key set by the operator for operating the register of the selected register sender to store up the desired number, 5 and means for operating the associated sender to transmit the stored up number of said train of switches to complete the connection.

33. In a telephone system, a group of 10 trunk lines, a group of register senders, a group of link circuits, a plurality of normally inoperative connecting means for connecting any one of said senders with any one of said lines through any one of said link 15 circuits, a set of number keys, a switch individual to said keys for connecting them with an idle link circuit, and means responsive to such connection for rendering operative the said connecting means that is associated with said idle link circuit.

34. In a telephone system, a plurality of 20 automatic register senders, a plurality of register-sender selectors, means for operating a register-sender selector to select an idle 25 register sender, means controlled through the register-sender selector in use for setting up a number on the selected registering mechanism, means responsive thereto for operating the selected sending mechanism to 30 send the registered number back through the selector in use, operator controlled means effective during the said registration of the number for releasing the selector to free the register sender, and means in the selector 35 controlled from the selected register sender for rendering said releasing means ineffective responsive to the completion of said registration.

35. In a telephone system, a plurality of 40 trunk lines, a plurality of senders, a plurality of link circuits for connecting any sender to any trunk line, a link allotter, means for automatically maintaining said allotter associated with an idle link circuit, and operator controlled means for advancing said 45 allotter independent of said automatic means.

36. In a telephone system, a plurality of 50 register senders, a plurality of trunk lines, a plurality of link circuits, each having mechanism for connecting any desired line with any idle register sender, a link allotter for allotting only one link circuit for use at one time, an assign key for each line, means 55 responsive to the operation of an assign key for causing the allotted link circuit to connect the line associated with the operated assign key with an idle register sender, means for operating the selected registering 60 mechanism through the link circuit in use to register a desired number, means for subsequently transmitting the registered number to the assigned trunk through the link circuit in use, and means responsive to the 65 complete registration of the number in the

register sender for operating said allotter to allot another link circuit.

37. In a telephone system, a plurality of 70 trunk lines extending to automatic switches, a plurality of register senders, a group of link circuits for connecting idle senders with trunk lines over which calls are to be extended, an operator's key set, preselecting switching means for maintaining said key set connected with an idle link circuit, means 75 responsive when the operator assigns one of said trunks to a call for causing the pre-selected link circuit to connect an idle register sender to the assigned trunk, circuit arrangements for causing a number set up on 80 said key set to be registered in the connected register sender, and means responsive to the registration of the last digit in the number for causing the connected register sender to transmit the number through the link circuit in use to the connected trunk line.

38. In a telephone system, a plurality of 85 trunk lines extending to automatic switches, a plurality of register senders, a group of link circuits for connecting idle senders with trunk lines over which calls are to be 90 extended, an operator's key set, preselecting switching means for maintaining said key set connected with an idle link circuit, means responsive when the operator assigns one of 95 said trunks to a call for causing the pre-selected link circuit to connect an idle register sender to the assigned trunk, circuit arrangements for causing a number set up on 100 said key set to be registered in the connected register sender, and means responsive to the registration of the last digit in the number for causing the said switching means to preselect another one of said link circuits.

39. In a telephone system, a plurality of 105 trunk lines extending to automatic switches, a plurality of register senders, a group of link circuits for connecting idle senders with trunk lines over which calls are to be extended, an operator's key set, preselecting 110 switching means for maintaining said key set connected with an idle link circuit, means responsive when the operator assigns one of said trunks to a call for causing the pre-selected link circuit to connect an idle register sender to the assigned trunk, circuit arrangements for causing a number set up on 115 said key set to be registered in the connected register sender, and means responsive to the registration of the last digit in the number for causing the connected register sender to transmit the number through the link circuit in use to the connected trunk line for causing the said switching means to preselect another one of said link circuits.

40. Operator's switch control equipment comprising a key set, a register sender, an automatic switch for connecting said key set and register sender, the connection including a plurality of conductors less than 120 125 130

five in number, contacts on said keys for connecting a source of current to said conductors singly and in combinations according to a preassigned code, sets of decoding relays in the register sender controlled over said conductors, the number of relays in each set being equal to the number of said conductors, a sending device in said register sender, and conductors extending from said sending device to multiply connected contacts on the relays of said sets.

41. In a telephone system, a trunk line, a register sender, a plurality of link circuits, each having mechanisms for connecting said line with said register sender, a link allotter for allotting only one link circuit for use at one time, means for causing the allotted link circuit to connect said line with said register sender, means for operating said register sender to register a desired number, means for subsequently transmitting the registered number to said trunk line through the link circuit in use, and means responsive to the complete registration of the number in the register sender and independent of any operation of the said sending mechanism for operating said allotter to allot another link circuit.

42. In a telephone system, a trunk line, a register sender, a plurality of link circuits, each having mechanisms for connecting said line with said register sender, a link allotter for allotting only one link circuit for use at one time, means for causing the allotted link circuit to connect said line with said register sender, means for operating said register sender to register a desired number, means for subsequently transmitting the

registered number to said trunk line through the link circuit in use, and means responsive to the complete registration of the number in the register sender and independent of other control to the complete registration of the number in the register sender for operating said allotter to allot another link circuit.

43. In a telephone system, a register, a register sender, a register controlling device, an outgoing control conductor, a local conductor extending from said controlling device to said register, means for operating said controlling device to set said register over said local conductor, means for disconnecting said local conductor from said register at one end and for extending it to said sender and for disconnecting said local conductor from said control device at the other end and for connecting it to said outgoing control conductor, and means for operating said sender under the control of said register to transmit impulses to said outgoing control conductor over said local conductor.

44. In a telephone system, an automatic switch, a register sender, an operator's key set, a pair of conductors terminating in said register sender, means for connecting said conductors to said key set for use in setting the registering portion of said register sender, and means for then shifting the said conductors to said switch for use in sending impulses to the switch from the sender.

Signed by me at London England, this 4th day of April, 1924.

RICHARD MERCER.
